MERCURY VAPOR RECTIFIER

Application filed May 23, 1928, Serial No. 279,907, and in Germany June 11, 1927.

This invention relates to mercury vapor rectifiers and has among its objects the provision of an improved screen for preventing backfiring or undesirable discharges from the anodes of such rectifiers.

The objects and features of the invention will be best understood from the following description of exemplification thereof, reference being had to the accompanying drawings, wherein—

Fig. 1 is a vertical sectional view through a metal tank rectifier embodying the invention;

Fig. 2 is a vertical sectional view through the anode and shield therefor, drawn in reduced scale, illustrating in detail the grid arrangement of my invention;

Fig. 3 is a horizontal sectional view through the shield arrangement along the lines III—III of Fig. 2;

Fig. 4 is a view similar to Fig. 2, illustrating a grid arrangement in which the anode grid is insulated from the shield chamber enclosing the anode.

My invention is of particular importance in connection with high power mercury arc rectifiers of the metal tank type, although it is not necessarily limited thereto, and some of its features are useful and of importance in rectifiers of other types. In order to illustrate the invention, it will be described as applied to a rectifier of the metal tank type as shown in section in Fig. 1 of the drawings. It comprises a hermetically closed vessel including a main arc chamber 1 and a condensing chamber 2 on the top thereof. The arc chamber is made of a steel cylinder 3, the upper end of which is sealed by a massive anode plate 4 also of steel or similar mercury

resistant material. At its lower end, the arc chamber cylinder 3 is closed by a bottom plate 5. The latter has in its middle an opening 6 which leads to the mercury container 7 formed of a short cylindrical body of insulating material such as porcelain that is closed at its bottom by a plate 8 of iron. A quantity of mercury 9 within this container serves as the cathode of the rectifier.

The anode plate 4 is likewise provided with a central opening over which is mounted the

condensing chamber 2 referred to above. This condensing chamber is formed of a main cylinder 11 that has its upper end closed by a metallic cover plate 11. In the center of this cover plate 12 is mounted the ignition coil 13 which operates the ignition electrode 14 to produce a current interrupting arc at the surface of the mercury cathode and thus start the operation of the rectifier.

Mounted circumferentially on the anode plate 4 around the condensing chamber 2 are a plurality of anodes 15, usually six or twelve in number, depending on the capacity of the rectifier. The anode 15 is made preferably in the form of a cylindrical thick walled member of steel having round edges and a short re-entrant portion at the lower end thereof. The interior of the anode 15 may be hollow and is joined to a stem 16 extending through an insulating bushing 17 mounted within a suitable opening in the anode plate to insulatingly support the anode therein. The upper end of each anode stem is provided with a suitable heat-radiating member 18 for dissipating the heat generated at the anode so as to maintain the same at a proper operating temperature.

The anode chamber 3, the condensing chamber 2, and the cathode bottom plate 8 are likewise cooled by means of suitable jackets with cooling fluid such as water that is suitably circulated. An exhaust connection from an evacuating pump (not shown) is provided at 19 on the cover plate of the condensing chamber 2.

All the several parts of the rectifier structure as described above are suitably joined to provide a hermetical enclosure and the interior of the vessel is highly evacuated.

The cathode 9 is held insulated from the remainder of the body of the rectifier vessel and special insulated funnel members 21 and 22 are provided in the interior of the chamber to return condensed mercury so as to prevent formation of a continuous thread of mercury that might tend to establish an electrically conducting connection between the mercury cathode and any of the metallic wall portions of the rectifier vessel.

For the operation of rectifiers of this type,

it is found important to enclose each anode in a shield 25 that opens toward the bottom so as to protect the anodes against the influences tending to destroy their valve action. 5 As seen in the drawings, the shields surrounding the anodes are made in the form of relatively long tubular members of sheet metal. The anodes with the shields are disposed on the sides of the rectifier tank, the shields 10 having openings at the bottom at a distance below the anodes and defining a substantial length of the arc path to the anodes. The shield openings are arranged to lie outside the space above the cathode area so that the 15 mercury blast from the cathode is prevented from entering into the shield.

As is well known, rectifiers of the foregoing type operate on the polyphase principle and each anode carries successively rectifying current during a portion of the rectifying cycle, this current flow being known as a "forward current flow". In the course of each alternating current cycle, the individual anodes are successively substituted one 25 for another, each carrying for a short period during which the respective anode is positive, forward current.

One of the drawbacks that the designers and operators of this type had to contend with in the past and which is particularly serious because of the large power and high voltages involved, was a tendency of such anodes to occasionally backfire or carry a reverse current during the period when the anode became negative with respect to the cathode. Much work was done heretofore by the designers of such rectifiers and many attempts were made to find a solution for this backfiring problem since the latter constitutes a very serious drawback and is one of the main reasons for the slow progress in adopting such rectifiers on a larger scale. 40

My invention is concerned with a new type of grid arrangement which greatly exceeds anything proposed heretofore in its ability to suppress backfiring in rectifiers of the type described above.

Referring to the drawings, the grid of my invention may have the form of a series of 50 concentrically disposed short sleeves 31, 32, 33 of thin sheet metal about one millimeter thick, located within the shield directly underneath the anode surface. The several cylinders 31-33, are held together by two stays 34, 35 disposed crosswise, one on the top and one on the bottom in short slots in the several cylinders and welded thereto so as to provide a substantially simple and relatively rigid body. By means of three or more spacing 55 tubes 36 of metal, and bolts 37, the grid is held fixed within the anode shield in its appropriate place. The simple grid structure described above and arranged in the way shown in the drawings has a surprisingly 60 strong effect in eliminating reverse current

flow or backfiring from the anodes and in this respect, acts entirely different from any of the screen arrangements proposed heretofore for similar purposes. Because of the particular importance of the relative location 70 of the parts and the spacing between the individual portions of the grids from the shield, as well as the spacings of the grid and the shield from the anode, I have indicated in Figs. 2 and 3 the actual dimensions of the 75 grid-shield structure which I found most beneficial in practical applications, the dimensions being given in millimeters. It is very important to maintain the proper ratios and it is particularly important that the distances between the several parts be maintained in accordance with the figures given in the drawings. As seen from a comparison of the dimensions in Fig. 2, the effective length of the anode shield or sleeve 25, i. e., the distance between the opening or mouth of the shield and the anode surface is relatively great compared with the distance of the grid from the anode and the length of the grid, although the latter extends over a substantial 90 part of the effective shield height. The entire grid is located in the upper third of the effective shield height, and the grid is higher than one-tenth of the effective shield height. The height of the grid is about five centimeters, and the distance between the grid and the anode surface is of the order of the height 95 of the grid. However, departures from these figures given by me will likewise approach the desirable results obtained by my screen structure, and it is understood that I do not wish to limit my invention altogether to grids having a particular set of dimensions.

One of the important features of the grid or screen structure is the fact that it is placed immediately adjacent the anode surface and that it is made entirely of metal. There is also a great advantage in building up the grids of comparatively thin sleeves or tubes so that they do not take up much space in a plane at right angles to the arc, and hence do not adversely affect the operation of the forward arc or rectifying current, or appreciably increase the voltage drop therein. I explain the beneficial effect of the grids of my invention by the fact that experiments and observations of the behavior of mercury vapor rectifiers have shown that as a general rule a backfire or reverse arc to an anode follows directly on the disappearance of the normal arc, that is to say, the normal or forward current reverses practically instantaneously. It is known that the cause of the backfire originates while the forward arc is operating and may be due to an incandescent spot on the anode owing to non-uniform operation of the arc or to an incandescent foreign body of the anode. The cause of the backfire usually disappears as soon as the normal or forward arc is extinguished. Thus, the develop- 110 115 120 125 130

ment of a backfire between the cathode or a normally operating anode and an anode which has for the time being assumed a negative potential may, it seems, be prevented by retarding the formation of the reverse arc following the extinction of the forward arc, to an extent sufficient to enable the causes of the backfire to be removed before the reverse arc has been started. It would seem that this is among others accomplished by the grid or screen structure located and arranged in the path of the arc as described above. It is understood, however, that I do not desire to limit myself to any particular theory of operation or functioning of my improved grids, but I desire to embrace all the grid structures which embody the principle of those described by me.

The employment of grids or screens such as used in the rectifier described above raises the striking voltage of the arc. This striking voltage will be higher in proportion to the length of the tubular members of the grid and the closeness with which they are spaced. As a consequence of the increased striking voltage, a rectifier fitted with grids of this description cannot always be directly connected to a system in which a back electro-motive force exists, for instance, a system having independent sources of direct current connected thereto. In such systems, the rectifier must usually be first connected through a resistance which may be cut out after the arc has been struck. The rectifier may be paralleled without the use of a resistance if the grids are first given a positive striking charge from an auxiliary voltage source. However, I have found that this is not always necessary and that under some conditions, it may be possible to operate rectifiers provided with such screens without any special paralleling resistance provided the rectifier has been initially treated so as to adapt the same to such operation.

The grid or screen structures are, of course, made of a metal which does not amalgamate with mercury, for example, iron. With heavy currents, however, iron is liable to melt or become friable and therefore in some instances a more refractory metal such as tungsten may be preferable. As pointed out before, grids of the above description are not confined in their use to metal case rectifiers, but are likewise suitable for other types of rectifiers, for instance, those of the glass bulb type. The invention is likewise not limited to grids using circular tube sections, but similar beneficial effects will be obtained with structures using other sections, for instance, checkered or corrugated tubular forms.

In some cases, it may be desirable to insulate the grid from the shield structure itself, such arrangement being shown in Fig. 4 in which the spacing tubes 41 between the screen and the shield are made of an insulating material, such as porcelain and the bolts 42 con-

necting the screen to the shield are likewise insulated from the shield by interposing suitable insulating washer 43. The advantage of mounting the grid in such a way lies in the possibility offered thereby of electrically interconnecting the grids of several anodes in the rectifier. Such arrangement furthermore permits giving the grids a positive striking or negative extinguishing potential with respect to the corresponding anode, or more generally, it permits independent control of the potential of the grids in case this is desired.

My invention is not limited to the particular details or features of construction, or the theory of operation pointed out above, and I desire accordingly, that the appended claims be given a broad construction commensurate with the scope of the invention within the art.

I claim:

1. In a vapor discharge device, an anode having an active surface and a grid positioned at a short distance in front of said surface comprising sheet metal members subdividing the space in front of said active anode surface into a plurality of channels leading in the direction of the arc, the material forming said channels occupying a relatively negligible portion of the space in a direction transverse to the arc and leaving the space between said members unobstructed, the length of said channels being approximately of the order of the distance between said grid and said active anode surface.

2. In a vapor discharge device, an anode, and a grid placed in the path of the arc to said anode, said grid comprising a plurality of concentrically arranged tubular members sub-dividing the arc space into a plurality of parallel arc channels leading to the anode.

3. In a vapor discharge device, an anode, a vaporizable cathode remote from said anode, a sleeve surrounding said anode and defining an arc path towards said cathode, said sleeve having an opening for said arc path at a distance from said anode and a grid across said arc path located within said sleeve nearer to said anode than to said opening, said grid constituting a plurality of longitudinal channels extending in the direction of the arc path.

4. In a vapor discharge device, an anode, a vaporizable cathode remote from said anode, a metallic sleeve surrounding said anode and defining an arc path towards said cathode, said metallic sleeve having an unobstructed opening for said arc path at a distance from said anode, and a metallic grid across said arc path located within said sleeve nearer to said anode than to said opening, said grid constituting a plurality of longitudinal channels extending in the direction of the arc path.

5. In a vapor discharge device, an anode, a cathode, a metallic sleeve surrounding said anode and defining an arc path towards said cathode, said sleeve having an opening for said arc path at a point relatively remote from the active anode surface, and a metallic grid disposed in said sleeve in the direction transverse to said arc path, said grid being located at a point in said shield nearer to said active anode surface than to said sleeve opening, said grid being formed of sheet metal portions constituting longitudinal channels in the direction of the arc path, said grid occupying a substantial length in the direction of said arc path and a substantially negligible area in the direction transverse thereto, leaving the space between said metal portions substantially unobstructed.

6. In a mercury vapor discharge device, an anode, a mercury cathode remote from said anode, a tubular metallic sleeve surrounding said anode and extending for a distance therefrom to define the arc path to said cathode, said sleeve having a substantially unobstructed arc-admitting opening at a distance from said anode, and a metallic grid disposed in said sleeve transversely to the arc at a distance equal or less than one-third of the distance between said anode and said opening, said grid constituting a plurality of longitudinal channels extending in the direction of the arc path.

7. In a vapor discharge device, an anode, a mercury cathode removed from said anode, a tubular metallic sleeve surrounding said anode and extending for a substantial length therefrom to define an arc path, an opening in said sleeve at a distance from said anode, and a metallic grid disposed within said sleeve transversely to the arc path, said grid comprising thin sheet metal members extending in the direction of the arc path to constitute a plurality of parallel arc channels, the distance between said grid and said anode surface being less than one-third of the distance between said anode surface and said shield opening, and the length of said channels being of the order of the distance between said grid and said anode.

8. In a vapor discharge device, a gas tight vessel containing a vapor, a cathode, an anode for maintaining a discharge with said cathode through said vapor, an insulated sleeve around said anode having an opening at a distance therefrom and confining a substantial length of the discharge path between said anode and said cathode, and sheet members subdividing a substantial length of said sleeve in front of said anode into longitudinal channels extending in the direction of the discharge toward said anode, said sheet members being of small thickness and occupying a substantially negligible area in the direction transverse to the discharge, leaving the space between said sheet members free for the passage of the discharge, said grid being nearer to the anode than to said sleeve opening.

9. In a vapor discharge device, a gas tight vessel containing a vapor, a cathode, an anode for maintaining a discharge with said cathode through said vapor, an insulated sleeve around said anode having an opening at a distance therefrom and confining a substantial length of the discharge path between said anode and said cathode, and sheet members subdividing a substantial length of said sleeve in front of said anode into longitudinal channels extending in the direction of the discharge toward said anode, said sheet members being of small thickness and occupying a substantially negligible area in the direction transverse to the discharge, leaving the space between said sheet members free for the passage of the discharge.

10. In a vapor discharge device, a gas tight vessel containing a vapor, a cathode, an anode for maintaining a discharge with said cathode through said vapor, an insulated sleeve around said anode having an opening at a distance therefrom and confining a substantial length of the discharge path between said anode and said cathode, and sheet members subdividing a substantial length of said sleeve in front of said anode into longitudinal channels extending in the direction of the discharge toward said anode, said sheet members being of small thickness and occupying a substantially negligible area in the direction transverse to the discharge, leaving the space between said sheet members free for the passage of the discharge, the length of said channels being not more than twice the smallest width of said channels.

11. In a vapor discharge device, a gas tight vessel containing a vapor, a cathode, an anode for maintaining a discharge with said cathode through said vapor, an insulated sleeve around said anode having an opening at a distance therefrom and confining a substantial length of the discharge path between said anode and said cathode, and metallic sheet members subdividing a substantial length of said sleeve in front of said anode into longitudinal channels extending in the direction of the discharge toward said anode, said sheet members being of small thickness and occupying a substantially negligible area in the direction transverse to the discharge, leaving the space between said sheet members free for the passage of the discharge.

12. In a vapor discharge device, a gas tight vessel containing a vapor, a cathode, an anode for maintaining a discharge with said cathode through said vapor, an insulated sleeve around said anode having an opening at a distance therefrom and confining a substantial length of the discharge path between said anode and said cathode, and a grid formed of metallic sheet members subdividing a substantial length of said sleeve in front of said anode into longitudinal channels extending in the direction of the discharge toward said anode, said sheet members being of small thickness and occupying a substantially negligible area in the direction transverse to the discharge, leaving the space between said sheet members free for the passage of the discharge, said grid being nearer to the anode than to said sleeve opening.

13. In a vapor discharge device, a gas tight vessel containing a vapor, a cathode, an anode for maintaining a discharge with said cathode through said vapor, an insulated sleeve around said anode having an opening at a distance therefrom and confining a substantial length of the discharge path between said anode and said cathode, and a grid

formed of metallic sheet members subdividing a substantial length of said sleeve in front of said anode into longitudinal channels extending in the direction of the discharge toward said anode, said sheet members being of small thickness and occupying a substantially negligible area in the direction transverse to the discharge, leaving the space between said sheet members free for the passage of the discharge, said grid being within 10 centimeters from said anode.

13. In a vapor discharge device, a gas tight vessel containing a vapor, a cathode, an anode for maintaining a discharge with said cathode through said vapor, an insulated sleeve around said anode confining a portion of the length of the discharge path extending from said anode to the cathode, and conducting partition members carried by said sleeve at a distance in front of said anode and subdividing the cross-sectional area of said confined discharge path into a plurality of longitudinal channels extending parallel to each other in the direction of the discharge, the transverse area occupied by said partition members occupying less than about one-fifth of the cross-sectional area of said channels, the length of said channels being of the order of their distance from said anode.

14. In a vapor discharging device, a gas tight vessel containing a vapor, a cathode, an anode for maintaining a discharge with said cathode through said vapor, an insulated sleeve around said anode having an opening at a distance therefrom and confining a portion of the discharge path between said anode and said cathode, and partition members supported by said sleeve in front of said anode and subdividing said discharge path into longitudinal channels extending in the direction of the discharge toward said anode, said partition members occupying a transverse area small compared with the cross sectional area of the channels, leaving the space between said partition members free for the passage of the discharge.

15. In a vapor discharge device, a gas tight vessel containing a vapor, a cathode, an anode for maintaining a discharge with said cathode through said vapor, an insulated sleeve around said anode having an opening at a distance therefrom and confining a portion of the discharge path between said anode and said cathode, and partition members supported by said sleeve in front of said anode and subdividing said discharge path into longitudinal channels extending in the direction of the discharge toward said anode, said partition members being of small thickness and occupying in the direction transverse to the discharge a small area compared to the area of said channels, leaving the space between said partition members free for the passage of the discharge, the length of said

channels being not more than twice the smallest width of said channels.

16. In a vapor discharge device, a gas tight vessel containing a vapor, a cathode, an anode for maintaining a discharge with said cathode through said vapor, an insulated sleeve around said anode having an opening at a distance therefrom and confining a portion of the discharge path between said anode and said cathode, and metallic partition members supported by said sleeve in front of said anode and subdividing said discharge path into longitudinal channels extending in the direction of the discharge toward said anode, said partition members occupying a transverse area small compared with the transverse area of said channels, leaving the space between said partition members free for the passage of the discharge.

17. In a vapor discharge device, a gas tight vessel containing a vapor, a cathode, an anode for maintaining a discharge with said cathode through said vapor, an insulated sleeve around said anode having an opening at a distance therefrom and confining a portion of the discharge path between said anode and said cathode, and a grid formed of metallic partition members supported by said sleeve in front of said anode and subdividing said discharge path into longitudinal channels extending in the direction of the discharge toward said anode, said partition members occupying a transverse area small compared with the transverse area of said channels, leaving the space between said partition members free for the passage of the discharge, said grid being within 10 centimeters from said anode.

In testimony whereof I have hereunto subscribed my name.

STEFAN WIDMER.
